CORN POPPING MACHINE

John Lindstrom, Montclair, and Burgess C. Case,
Plainfield, N. J.

Application November 15, 1947, Serial No. 786,190

4 Claims. (Cl. 99—238.2)

1

This invention relates in general to improvements in the construction and mode of operation of corn popping machines, and, more particularly, of coin-operated automatic corn popping machines, which, on the insertion of a coin with the machine in its normal operating condition, will pass through a cycle of operations beginning with the loading of a corn cup with raw corn, the movement of the loaded cup into a dumping position relative to a perforated popping basket reciprocating in a bath of hot cooking oil, the return of the cup to its loading position, the popping of the raw corn for a predetermined time, and the lifting of the reciprocating popping basket out of the bath to a position where the popped corn is discharged through a chute into a bag, such as disclosed in Case U. S. Patent No. 2,216,805.

The general object of the present invention is the provision of a corn popping machine of the character described which is further characterized by its ease and relatively low cost of manufacture, simplicity of operation, and facility for cleaning and repair. A more specific object is the provision of a machine of the character described having a minimum number of parts and in which substantially all of the parts are made of stampings and die castings. Another specific object is the provision of a raw corn tank for such machines having an improved bottom construction facilitating the discharge of raw corn. Another specific object is the provision of a raw corn cup for such machines having a combined bottom support and counterbalance capable of adjustment for varying the volumetric capacity of the cup. Another specific object is the provision of a popping basket for such machines having a special door construction for preventing dripping of cooking oil therefrom. Another specific object is the provision of an improved cooking oil pan construction requiring only a relatively low volume of cooking oil while providing a relatively high rate of heat transmission. Another specific object is the provision of an improved float control mechanism providing an accurate control of the cooking oil level in the pan at all times and actuating the coin rejecting mechanism whenever the oil level falls below a predetermined value. Another specific object is the provision of a process of and control mechanism for maintaining the corn popping period and oil temperature within a critical time and temperature range respectively. Another specific object is the provision of electrically operated control mechanism for actuating the coin mecha-

2

nism to reject all coins during the initial period of heating the cooking oil and to prevent the float control mechanism from being actuated during that period.

5 The various features of novelty which characterize the invention are pointed out with particularity in the claims annexed to and forming a part of this specification. For a better understanding of the invention, its operating advantages and specific objects obtained by its use, reference should be had to the accompanying drawings and descriptive matter in which is illustrated and described a preferred embodiment of the invention.

10 15 Of the drawings:

Fig. 1 is a front elevation of a corn popping machine constructed in accordance with the invention, the front door being open to show the internal arrangement;

20 Fig. 2 is a sectional elevation of the operating mechanism taken on the line 2—2 of Fig. 3;

Fig. 2^a is a plan view of the pan filler block;

Fig. 3 is a rear view of the operating mechanism;

25 Fig. 4 is a perspective of a portion of the operating mechanism;

Fig. 5 is a vertical section of the drive mechanism taken on the line 5—5 of Fig. 6;

30 Figs. 6 and 7 are plan and side views respectively of the drive mechanism shown in Fig. 5;

Fig. 8, 9 and 10 are elevations of the loading, agitator, and dumping cams respectively;

35 Figs. 11, 11^a and 12 are side, fragmentary bottom plan, and bottom views respectively of the raw corn tank;

Fig. 13 is a sectional elevation of the corn cup;

Figs. 14, 15 and 16 are plan, elevation and front views respectively of the popping basket;

40 Fig. 16^a is an enlarged sectional elevation of the popping basket door;

Fig. 17 is an elevation, partly in section, of the cooking oil tank assembly;

Fig. 18, 19 and 20 are elevation, plan and end views respectively of the float control mechanism;

45 Fig. 21 is a sectional elevation of the motor switch assembly;

Fig. 22 is a schematic wiring diagram of the machine;

50 Fig. 23 is a diagrammatic view showing the sequence of the timing relays; and

Fig. 24 is an end view of the corn chute.

The automatic corn-operated corn popping machine illustrated in the drawings is contained by a cabinet 30 of substantially rectangular hori-

zontal and vertical cross-section having a front door 31 containing an opening 32 for the insertion of a bag by the customer into an open-faced shell forming a bag receiver compartment 33 and supported on a chassis 34 removably mounted on brackets secured to the side walls of the cabinet. A door slot 35 provides access to a bag dispenser 36 on the chassis 34. A tapering corn chute 37 opens through the top of the compartment 33. The upper part of the cabinet contains a raw corn tank 38 and a cooking or seasoning oil tank 39.

As shown in Figs. 2 and 3, in accordance with the invention the tanks 38 and 39 are adjustable mounted on the side walls of the cabinet and chassis to facilitate the proper positioning of the tanks relative to the operating mechanism. The corn tank 38, for example, has an upper angle bracket 40 on its outer side arranged to fit over an oppositely arranged angle bracket 41 on the cabinet side wall. The lower end of the tank carries a pair of flattened U-shaped brackets 42 secured in position by nuts 45 on threaded studs 43 on the cabinet projecting through vertical bracket slots 44. Adjusting screws 46 on flanges 47 projecting from the cabinet wall abut the lower flanges of the brackets 42 to position the tank at the desired level. A vertically adjustable standard 48 mounted on the chassis has its upper end shaped to form a shelf on which the lower inner edge of the tank 38 rests. A similar supporting arrangement is used for the cooking oil tank 39.

The tanks 38 and 39 have removable tops, to which access is had through the hinged top 49 of the cabinet. The corn tank, as shown in Figs. 11, 11^a and 12, has a special bottom construction for facilitating the discharge of the corn kernels. The tank bottom 50 is flat with an ovate corn discharge opening 51 adjacent its inner end. An inclined baffle 52 extends downwardly from the outer wall of the tank to form a tapering false bottom and is bent and cut away to contact with the bottom plate around the opening 51, the edges of the cut out portion 53 being slightly spaced from the opening to form a narrow ledge 54, as shown in Fig. 11^a, which causes the kernels to tumble in passing to the discharge opening.

The discharge of corn through the opening 51 is controlled by the position of a shut-off slide 56 mounted in guide plates 57 on the tank bottom and spring loaded by a pair of tension springs 58 extending between the outer flanged end of the slide 56 and the inner flanged ends of the plates 57, as shown in Fig. 12. The inner end of the slide carries a plate 59 on its underside having a depending curved lip 60 adapted to contact with a corn cup 88 hereinafter described. An agitator finger 62 detachably mounted on the inner end of the slide extends upwardly through the tank opening 51 to prevent the corn in the tank from bridging adjacent the discharge opening. The inward movement of the slide is limited by contact of the outer flanged end of the slide with the outer ends of the guide plates 57, as shown in Fig. 12. A depending flange 63 on the slide is contacted to move the slide outwardly against the springs 58 as the corn cup is moved into its loading position. The finger 62 fits into the smaller end of the opening 51 in the retracted position of the slide.

The driving mechanism of the machine comprises a constant speed capacitor type electric motor 65 driving a shaft 66 carrying a worm 67 meshing with a worm wheel 68 on a shaft 69.

The shaft 69 carries a worm 70 meshing with a worm wheel 71 on a shaft 72. A popping basket reciprocating or agitator cam 74, shown in Fig. 9, is mounted on the shaft 69. The shaft 72 has a loading cam 75, shown in Fig. 8, and a dumping cam 76, shown in Fig. 10, mounted on the rear and front ends thereof respectively.

The loading cam 75 is of the internal type and has a cam groove 77 in its rear face in which rides a cam roller 78 carried by a plate 79 pivoted on a pivot shaft 80. The cam groove is shaped with a single peak or lobe 81 which causes the roller 78 and plate to oscillate about the axis of shaft 80 to move a vertical arm 82, bolted to the outer edge portion of the plate 79, between corn loading and dumping positions. The arm passes through a slot in a guide plate 83. A horizontally arranged finger 84 is secured on the upper end of the arm 82, with its outer section 84^a curved upwardly as shown in Fig. 3 to abut the inner face of the flange 63 and its inner section 84^b rearwardly offset and arranged to abut an upwardly curved tongue 85^a on the cover 85 of a popping basket 94. The arm 82 also carries an L-shaped bracket 86, the flexible vertical leg of which is slightly spaced from the arm and terminates in a yoke 87, in which the corn cup 88 is pivotally mounted.

The corn cup 88, as shown in Fig. 13, is formed by a cylindrical open-ended shell having openings 89 for the yoke pivot pins. At the start of the operating cycle, the slide 56 is retracted and the cup in its loading position shown in Fig. 3 where it fills by gravity through the corn tank hole 51. As the loading cam actuates the cup arm 82 to move the loaded cup from under the tank, the shut-off slide follows to cover the bottom of the hole 51 and prevent any corn from spilling through the hole. As shown in Figs. 3 and 11^a, the hole 51 is not completely closed in the inner position of the slide. The corn cup is constructed so that its center of gravity when fully loaded will be in vertical alignment with its pivot axis, and when empty will be outwardly offset, so that the cup will be tilted with its upper end towards the corn tank during its return movement. For this purpose and to provide a volumetric capacity adjustment, a false cup bottom 90 is stepped and adjustably supported by a bracket 91 held in position by a stud 92 extending through a vertical slot 93 in the shell. The bracket and stud provide the necessary counterbalance to tilt the cup when empty. The tilt of the cup facilitates its passage below the corn tank lower inner edge when returning to its loading position, which is desirable as the clearance between the tank and cup to enable free travel of the cup is normally only $\frac{1}{32}$ ". The normal position of the corn cup relative to the tank is adjustable by loosening the bolts 82^a holding the arm 82 on the plate 79 and shifting the location of the lower bolt in an arcuate slot 82^b in the plate.

The corn popping basket 94, as shown in Figs. 14-16, is of substantially rectangular cross-section with imperforate side and rear walls, a perforate stepped bottom 95, a front discharge door 96 hinged at its lower end, and a top 97 closed except for a hinged cover 35. A hinge spring 98 maintains the cover closed until the finger 84^a rides on the tongue 85^b to raise the cover to allow the corn cup to dump. Dumping is effected by the corn cup engaging a snubbing post 100 which is vertically adjustable on the outer side of the basket midway of its length and formed by a plate 75 bent as shown in Fig. 16 to have an outwardly

inclined section 100^a, an inwardly inclined section 100^b, and a downwardly and inwardly extending section 100^c. As shown, the section 100^a is inclined approximately 15°, section 100^b is 27°, and section 100^c is 45° from the vertical. The loaded corn cup is moved laterally until its lower edge contacts with the post section 109^b, causing the cup to tilt about the pivot axis, and the continued movement of the arm 82 flips the pivoted cup over the top of the post sufficiently to discharge all of the corn therein down the surface of the post section 109^c into the popping basket.

The stepped perforated popping basket bottom 95 facilitates the entrance and drainage of cooking oil during operation. The basket discharge door 96, as shown in Fig. 16^a, has a two-part construction to eliminate any dripping of oil therefrom when in the corn discharging position, consisting of a solid outer plate 102 hinged at its lower edge on a hinge pin 103 on the basket and arcuate side wings 104 to confine the popped corn when discharging. The side edges of the plate forwardly of the wings are bent inwardly to provide guide flanges 105 for a perforated inner plate 106 which is also hinged on the pin 103 and extends in slightly spaced relation to the plate 102. The spacing is maintained and the upper end of the interplate space closed by bending over the discharge edge of the plate 106 to contact with the plate 102. The portion 106^a of the plate 106 along its bent edge is left solid to form in effect a shallow closed pocket along the discharge edge of the door.

The popping basket is reciprocably supported as hereinafter described in a rectangular pan 110 for holding the cooking oil, as shown in Figs. 2 and 4. A forwardly curved leaf spring 109 removably mounted on the front side of the pan continuously presses against the basket door 96 and holds the door in its closed position while the basket is reciprocated within the pan. The spring curvature permits the basket to be returned to its normal position in the pan without interference. The rear section of the pan is formed as a control float chamber 111 by a vertical transverse baffle 112 having openings 113 therein for the passage of the oil. The amount of oil required for a predetermined oil level in the pan 110 is substantially reduced by the positioning of a solid filler block 115 of high thermal conductivity metal, such as aluminum, in the basket compartment. The block has a longitudinal recess 116 in which a thermal bulb 117 is removably secured by suitable clips. The block is cut away along its bottom and rear sides to permit the flow of cooking oil to and from the float chamber 111 and to facilitate removal of the block. The thermal conductivity and heat storage capacity of the filler block is substantially equivalent to that of a similar volume of cooking oil, whereby the volume of oil in the pan is substantially reduced without affecting the level of oil in the popping basket, but correspondingly reducing the cleaning and odor eliminating problems encountered in operation.

The cooking oil pan is heated by a radiation type electric heater 120 consisting of a plurality of serially connected heating coils 121 having insulated supports from a surrounding rectangular frame 122 below the pan and mounted on a base plate 123 formed of artificial stone, which serves to reflect most of the heat radiated by the heating coils, thus substantially minimizing the rate of crystallization of the heating coils. The pan 110, heater 120, and base plate 123 are supported

in a rectangular metal oven 125. The electric current supply to the heater is provided through terminals 126 and leads 127.

The popping basket is continuously horizontally reciprocated throughout the operating cycle. This movement is effected by a lever 130 having a fixed pivot 129 at its lower end and carrying a cam roller 131 adjacent thereto positioned in a groove 132 in the outer face of the agitator 10 cam 74 which is formed as shown in Fig. 9 with symmetrically spaced points 133, over which as the cam rotates at a constant speed, the roller on the lever is moved forwardly and rearwardly. This motion is transmitted to the basket by a linkage consisting of a horizontal link 134 connecting the lever 130 to a yoke 135 pivoted on a pair of arms 136 projecting from the sides of the oven 125 and with the upper ends of the yoke arms pivotally connected to a pair of projecting horizontal support arms 137 secured to the sides of the basket and holding the basket at the desired level in the pan 110.

Near the end of the operating cycle the popping basket is lifted out of the pan 110 in order to dump the finished corn into the delivery chute 37. For this purpose the dumping cam 76 shown in Fig. 10 is synchronized with the loading cam 75 so that the cam 76 depresses a cam roller 141 carried by a lever 142 pivoted on the shaft 80 at the end of the desired popping period. The free end of the lever is connected to a yoke 143 pivotally connected to the front ends of the basket arms 137 through an adjustable link 144 having a ball and socket joint 145. The yoke arms 135 and 143 are detachably mounted on pivot pins on the basket arms 137 to facilitate the removal of the basket for cleaning. The dumping height of the basket can be raised or lowered by this screw adjustment on the ball and socket joint. The loading and dumping cams are timed to allow a delay of several seconds between the dumping of the popped corn and the loading of fresh corn into the basket, to compensate for possible override of the motor after the current supply is cut off.

The cooking or seasoning oil reservoir tank 39 is designed to use any standard type of cooking compound of the liquid, solid or hydrogenated type, a cocoanut base oil being preferred however having a melting temperature of approximately 76 F. To insure an adequate supply of liquified oil, an electrically operated immersion heater 150 is installed in the bottom of the tank. This heater maintains the temperature of any solid cooking compound above its liquifying point. A screened standpipe 151 in the tank maintains a minimum level of oil above the heater 150 to protect the heater from overheating. The oil flows by gravity from the standpipe 151, the bottom of which is closed by a cleanout plug 152, to a spring loaded solenoid operated control valve 153 and discharge pipe 154. The lower end of the pipe 154 is flattened, as shown in Fig. 17, and positioned within and along one side of the pan float chamber 111.

The oil level in the float chamber 111 and thereby also in the basket section of the pan is controlled by a pancake type elongated float 155 carried on a bracket 156, the outer end of which is pivotally mounted on an external standard 157. The bracket carries one end of a flat spring switch contact 158 which is moved by the rise and fall of the float away and towards respectively a stationary spring contact 159. The ratio of oil rise to switch movement is approximately 2:1.

Closing of the contacts 158, 159 is arranged to energize the solenoid valve 153 and allow a gravity flow of oil to the pan 110. The rate of flow of oil through the valve is made approximately the same as the oil consumption during the popping cycle. The spring contacts 158, 159 are carried on a bracket 160 which is vertically adjustable on the standard 157 by an adjusting screw 161 movable in a vertical slot 162 on the standard. The standard carries a zero marking, while the bracket 160 has scale graduations thereon to standardize the adjustment thereof effected. Lowering of the switch bracket in the standard will lower the cooking oil level maintained and vice versa. Too high an oil level is a waste of cooking oil, while too low a level will result in unpopped or incompletely popped corn. The desired level is initially determined when the oil is at approximately operating temperature. As indicated in Fig. 22, the solenoid is in the same circuit as the coin mechanism and float switch.

The corn chute 37 extends through the upper side of the shell 33 forming the bag receiver compartment with its upper part supported from the oven 125. As shown in Figs. 2 and 24, the lower end of the chute has a rounded front edge 140 and its opposite sides 140^a indented in a curved cross-section and an upwardly flaring formation to facilitate the mounting of satchel bottom type bags thereon by the customer. The rounded leading edge tends to flatten the sides of the bag, while the indented side portions of the chute accommodate the folds in the bag sides and gradually flare the bag sides as the bag is pushed on the chute end and then left resting on the bottom of the shell 33.

The motor switch assembly 170 shown in Fig. 21 is a limit switch to start the machine on the insertion of a coin and shut off the machine at the completion of the operating cycle. An adjustable operating bar 171 is pivotally connected to one side of the yoke 143 and is moved downwardly as the popping basket is raised to its dumping position. The bar carries a spring-pressed pawl 172 pivoted thereon which moves past a second spring-pressed locking pawl 173 pivoted on the switch box. The pawl 173 when in its locking position holds a flange 174 on a lever 175 pivoted on a bracket 161 from moving upwardly under the action of a spring 176. The lever 175 also has an insulated support 182 carrying one end of a spring contact 177 which is movable between upper and lower spring contacts 178 and 179. The lever 175 is pulled downwardly by the closing of a snap switch in the coin control mechanism momentarily exciting a solenoid 180, allowing the locking pawl 173 to engage the flange 174 and hold the contacts 177, 179 closed. As the basket is returned to its initial position at the end of the operating cycle, the bar 171 is raised, causing the pawl 172 to engage and turn the pawl 173, as indicated in Fig. 21, to release the flange 174 and lever 175, which under the action of the spring 176, will move upwardly to open the contacts 177, 179 and close the contacts 178, cutting off the power to the motor 65 and stopping the cycle.

The hollow thermal bulb 117 is immersed in the cooking oil pan and positioned close to the surface of the oil, so as to transmit the temperature of the oil in which the corn is popped as accurately as is possible. The normal oil level is approximately one inch above the top surface of the filler block 115, and the popping basket positioned to normally have a depth of approxi-

mately one-quarter inch of oil therein in the lower bottom section in operation. The thermal bulb and the flexible tube 185 connected thereto are filled with an expansion fluid and arranged to operate an on and off switch 186 controlling the power supply to the heater 120.

In accordance with the invention, the thermostat system and motor speed are set to maintain a predetermined popping temperature and period. For best results a high grade hybrid type pop corn having a moisture content not less than 12% should be used. When a hydrogenated vegetable compound, such as cocoanut or cotton-seed oil, is used as the cooking oil, with the corn immersed therein, it has been discovered that a popping period of 55-65 seconds, and preferably approximately 60 seconds, coupled with a cooking oil temperature in the range of 400-415 F., and preferably 407-411 F., will give the maximum popping efficiency. The thermostat control is arranged to maintain the cooking oil temperature within this 5° F. range. A lesser popping period with this temperature range would not pop all the corn in the charge. Too high a popping temperature prevents the corn from exploding to its maximum volume, causing it to be hard and tough, while a popping temperature below this range results in a rate of heat input to the corn too slow to secure the maximum popped volume.

The control switch box assembly 190, diagrammatically indicated in Fig. 22 consists of a key-operated main on-and-off control switch 191, a terminal block 192, a single pole single throw relay 193, and a double single pole single throw relay 194. When the machine is started at room temperature, a delay of 25-30 minutes is necessary before the oil is heated to the desired popping temperature range. During this heating-up period, it is essential that the coin mechanism does not accept any coins. Since the required heating-up period will vary with the ambient temperature, a definite period cannot be set, and the thermostatic control of the heater 120 through the switch assembly 190 is advantageously used for this purpose. As diagrammatically shown in Fig. 23, when the machine is in the "off" position, the contacts 193^a of the relay 193 are closed and the relay 194 has one pair of contacts 194^a in the thermostat circuit open and the other pair 194^b in the coin control circuit closed. When the machine is started, the thermostat controlled contacts are closed. Operation of the key switch 191 causes current to flow through the coil of the relay 193 and break the contacts 193^a controlled thereby. However, before this circuit is broken, current flows through the switch to the coil of the relay 194, causing the contacts 194^a to close and the contacts 194^b to open. This coil is then kept energized by the thermostat switch being in series therewith. Thus the momentary energizing of the double S. P. S. T. coil 194 by the S. P. S. T. relay 193 puts the coil of the double S. P. S. T. relay in series with the thermostat. The relay 194 remains energized until the thermostat switch 186 opens when the oil is heated to the desired temperature, at which time the relay 194 returns to its normal position. If the thermostat switch 186 should again close while the oil is at the proper temperature, the coil of the relay 194 will not be energized since the contacts 193^a of the relay 193 are open, as well as the pair of contacts 194^a of the relay 194 which are in series with the thermostat switch. This method of timing con-

trols exactly the heating-up period of the machine, during which time no current will be supplied to the coin mechanism which is therefore inoperative and will reject all coins. When the machine is up to its normal temperature range and the thermostat shuts off the flow of current to the heater, the relay 194 permits the coin mechanism to operate normally. The relays 193 and 194 thus function to insure that no coin will be accepted until the machine is in condition to deliver popped corn to the customer. A secondary function of the relays 193, 194 is to keep inactive the float control switch during the heating-up period. This prevents the solenoid valve 153 from opening and allowing cooking oil to enter the pan before the oil in the pan has expanded to its maximum volume. This prevents the accumulation of excess oil in the pan during the heating-up period, and also prohibits the solenoid valve from overheating. If for any reason the relay 194 is thrown out during a popping cycle, the described sequence of operation will take place. The machine will stop until the thermostat has cut out, and thereupon the relay 194 will automatically reset, allowing the machine to complete the cycle.

The coin control mechanism 200, diagrammatically indicated in Fig. 22, is of any suitable gravitational selector type in which a predetermined coin will actuate a spring arm to close the electrical circuit through the main motor switch relay solenoid 180 for a sufficient time interval to permit the locking pawl 173 to swing into position to hold the contacts 177, 179 closed. The electrical system includes a fluorescent lamp 201 in the top of the cabinet and knife switches 202 at convenient locations.

The operation of the machine will be apparent from the foregoing description of the operating parts and their functioning. With the machine in its normal operating condition, the insertion of a predetermined coin in the coin control mechanism starts the operating cycle. The drive mechanism moves the loaded corn cup 88 in an arc about the pivot shaft 80, in the course of which movement the finger 84^b opens the door 85 in the oscillating popping basket. The continued movement of the basket causes the corn cup to engage the snubbing post 100 and dump its load of corn into the oscillating basket. The cup then returns to its loading position and the basket door closes automatically. The dumped corn is distributed over the lower basket bottom perforated section and substantially covered by the layer of hot cooking oil therein maintained in the temperature range of 407-411 F. The preferred popping period insures the popping of substantially every kernel of corn, so that when the dumping cam is actuated to raise and tilt the oscillating popping basket, all of the corn will be discharged in a popped condition. The shut-off slide 56 insures that no raw corn is discharged while the corn cup is moving away from and returning to its loading position. The popping of the corn in the cooking oil results in the absorption of approximately three-fourths of an ounce of oil in each charge popped. The loss of oil is automatically replaced by the float control activating the solenoid valve 153. As the basket lifts to dump the popped corn, the liquid level will drop still farther due to the loss of the basket displacement, which will be restored to raise the oil level when the basket returns. The float control system is set to compensate for the displacement effect when the basket is returned. The popped corn cascades out of the popping basket through

the chute 37 into the bag inserted by the customer in the compartment 33. The operating cycle continues until the popping basket returns to its normal horizontal position in the pan 110.

5 At this point the motor switch is actuated to shut off the current supply to the motor and complete the cycle. The complete cycle requires seventy-five seconds with a popping period of sixty seconds. The insertion of another coin will cause 10 the cycle to be repeated.

While in accordance with the provisions of the statutes we have illustrated and described herein the best form of the invention now known to us, those skilled in the art will understand that 15 changes may be made in the form of the apparatus disclosed without departing from the spirit of the invention covered by the claims, and that certain features of the invention may sometimes be used to advantage without a corresponding 20 use of other features.

We claim:

1. In a corn popping machine, means forming a popping chamber adapted to receive a supply of cooking oil and raw corn, electrical means for 25 heating said chamber, an electrically operated coin control mechanism, and an electrical control system comprising a thermostatic switch responsive to the temperature of said chamber for controlling said heating means, means comprising 30 a relay arranged to be momentarily energized on the closing of said thermostatic switch, and a second relay having one pair of contacts in series with said thermostatic switch arranged to be closed on energization of said first named relay 35 and a second pair of contacts in series with said coin control mechanism arranged to be opened on energization of said first named relay.

2. In a corn popping machine, means forming a popping chamber adapted to receive a supply 40 of cooking oil and raw corn, electrical means for heating said chamber, an electrically operated coin control mechanism, and an electrical control system comprising a thermostatic switch responsive to the temperature of said chamber for controlling said heating means, means comprising 45 a single pole single throw relay arranged to be momentarily energized on the closing of said thermostatic switch, a double single pole single throw relay having one pair of contacts in series with said thermostatic switch arranged to be closed on energization of said first named relay, and a second pair of contacts in series with said coin control mechanism arranged to be opened on energization of said first named relay, 50 and means for opening said first pair of contacts and closing said second pair of contacts on the opening of said thermostatic switch.

3. In a corn popping machine, means forming a popping chamber adapted to receive a supply 55 of cooking oil and raw corn, means for supplying raw corn to said popping chamber, valve controlled means for supplying cooking oil to said popping chamber, electrical means for supplying heat to said popping chamber, an electrically 60 operated coin control mechanism arranged to initiate a popping cycle on the insertion of a coin therein, and an electrical control system comprising a normally closed thermostatic switch responsive to the temperature in said popping 65 chamber and set to open when a predetermined operating temperature is reached, means for rendering said coin control mechanism operative when said predetermined operating temperature is reached, means for maintaining said cooking 70 chamber and set to open when a predetermined operating temperature is reached, means for rendering said coin control mechanism operative when said predetermined operating temperature is reached, means for maintaining said cooking oil supply means in a closed position until said

predetermined operating temperature is reached, and mechanical means for ending said popping cycle after a predetermined time interval.

4. In a corn popping machine, means forming a popping chamber adapted to receive a supply of cooking oil and raw corn, means for supplying raw corn to said popping chamber, valve controlled means for supplying cooking oil to said popping chamber, electrical means for supplying heat to said popping chamber, an electrically operated coin control mechanism arranged to initiate a popping cycle on the insertion of a coin therein, and an electrical control system comprising a thermostatic switch responsive to the temperature in said popping chamber and arranged to render said heat supplying means inoperative when a predetermined operating temperature is reached, means for rendering said coin control mechanism operative when said predetermined operating temperature is reached, means for maintaining said cooking oil supply means in a closed position until said predetermined operating temperature is reached, and mechanical means for ending said popping cycle after a predetermined time interval.

JOHN LINDSTROM.
BURGESS C. CASE.
